UNITED STATES PATENT OFFICE.

THOMAS BOWES, OF CARLISLE, ENGLAND.

SOAP-HOLDER.

1,117,634.

Specification of Letters Patent. Patented Nov. 17, 1914.

Application filed May 17, 1912. Serial No. 698,011.

To all whom it may concern:

Be it known that I, THOMAS BOWES, subject of the King of Great Britain, residing at Denton Holme, Carlisle, in the county 5 of Cumberland, in the Kingdom of England, have invented certain new and useful Improvements in Soap-Holders, of which the following is a specification.

This invention has for its object a device 10 for use in lavatories to prevent unnecessary waste in the use of soap.

In the accompanying drawings, Figure 1 is a perspective view of my soap holder; Fig. 2, a cross section thereof; and Figs. 3, 15 4 and 5 are cross sectional views showing slight modifications in the soap holder.

Referring first to Figs. 1 and 2, the invention embodies a box or receptacle A having a bead A' around its edge and provided with wires B on one face, so as to form a cross. This box is adapted to receive a cake of soap C, so that one face of the soap will be exposed through the cross, while at the back of the cake of soap, is 20 a plate D with a spiral spring E behind, adapted to keep the soap pressed against the cross and against the bead or flange A'. Behind the spring E is the lid F, which forms a base for the spring, and insures 25 the spring exerting a pressure against the soap, which keeps it pressed against the wire cross and flange and extrudes it through the perforations, as the soap wastes away in use. This lid is fastened in any 30 convenient manner to the box or receptacle so as to be easily opened, as by catches G on the box adapted to engage the flanges H on the lid, so that by pressing back the lid and pressing the catches outward, the lid 35 can be taken off. The lid is supplied with an india-rubber scrubber I. In thus describing the invention, I wish to point out that in place of the wire grid B, a perforated plate J, (Figs. 3 and 5) may be 40 used; and instead of scrubber I, a brush K, (Fig. 3) may be employed or even a slab 45 of pumice stone L (Figs. 4 and 5).

The fastening for the lid in Figs. 4 and 5 is similar to that already shown in Fig. 50 2, but in Fig. 3 the lid is a fixture, and in order to replenish the receptacle with soap, the perforated plate J is made removable, being arranged at the edges J' so as to snap on to the edges of the box A. Instead of 55 the perforated plate, a reticulated plate M

(Fig. 4) may be provided with wires running in two directions. This is more especially useful for coarsely granulated soap N shown in Fig. 4.

Instead of using a cake of soap, as shown 60 in Figs. 1 and 2, nearly used up pieces of soap C' (Fig. 3) may be placed within the box.

O (Fig. 1, dotted lines) is an eye piece for attaching the device by a chain to some 65 permanent object to prevent it being taken away. Instead of the spiral spring E, a bent plate spring P may be used, (Fig. 4), or even a pneumatic cushion Q (Fig. 5).

There is space between the meeting edges 70 of the lid F and receptacle A, or perforations in the lid F through which any water collected in the receptacle can run out.

I do not confine myself to the receptacle 75 being made rectangular in shape, as it can be any suitable shape to conform to the shape of a cake of soap, and the perforated or reticulated face of the box can be made convex to conform to the convex shape of 80 an ordinary soap tablet.

The mode of action is as follows:—Soap having been placed in the receptacle A and the lid fastened down, the person using it uses the receptacle with the soap in it just 85 as if it was a piece of soap itself. The soap projects from the perforations or openings, and is worn away in the hands like ordinary soap. The user can at the same time use the other side of the box for an 90 abrasive or brush. When the box stands on the brush or on the scrubber, any water collected in the spring chamber will run out between the meeting edges of the lid F and the box A. The bead or flange A' 95 and the cross wires B impress themselves into the soap, so that the soap projects through the openings.

I declare that what I claim is:—

A soap holder, comprising a receptacle 100 having one face thereof reticulated and the other face thereof removable to permit the insertion of the soap, a plate located within said receptacle and adapted to engage said soap and press the same against the reticulated face of the receptacle, a spring interposed between said plate and the removable face of the receptacle, spring catches attached to the receptacle and having hooked ends normally overlying the opening in the 105 110

receptacle closed by said removable face, and said removable face of the receptacle having an outwardly projecting flange forming a recess for a scrubbing material and 5 forming locking devices adapted to engage the hooked ends of the catches.

In witness whereof, I have hereunto

signed my name this 7 day of May 1912, in the presence of two subscribing witnesses.

THOMAS BOWES.
